TOWEL CABINET

Jens Christian Jensen, Chicago, Ill., assignor to
 Northern Paper Mills, Green Bay, Wis., a corporation of Wisconsin

Application April 24, 1939, Serial No. 269,748

3 Claims. (Cl. 312—60)

This invention relates to improvements in cabinets for containing folded paper towels which are withdrawn for use from a slot in the bottom of the cabinet.

The object of the invention is the provision of a guard normally covering and protecting the exposed end of the paper towel projecting through the slot which is normally held in closed position by spring means necessitating the use of one hand for holding it in open position while withdrawing the paper towel with the other hand, thereby involving a slight delay in the withdrawal of the towels from the cabinet and discouraging extravagant and wasteful use thereof.

In the accompanying drawing wherein an approved embodiment of the invention is illustrated: Fig. 1 is a front elevation of the improved cabinet.

Fig. 2 is a side elevation thereof.

Fig. 3 is a fragmentary view similar to Fig. 2 but showing the lower portion of the cabinet in section and the guard member in open position.

Fig. 4 is an enlarged vertical section on the line 4—4 of Fig. 1 showing the hinged front part of the cabinet swung downwardly to open position to enable the introduction of a fresh supply of paper towels.

Fig. 5 is a bottom plan view of the cabinet showing the guard member in open position.

Referring to the drawing in detail, the body of the towel cabinet is composed of two parts designated at 6 and 7. The part 7 constitutes the rear wall of the cabinet and is rigidly secured to a wall or other support 8 by suitable means 9. The vertical edges of the stationary part 7 are bent angularly as indicated at 10 and the lower extremities of these flanges are extended downwardly and forwardly as at 11 and support pivot pins 12 which pass through the opposite side walls of the front part 6 and thereby pivotally connect the parts 6 and 7 together.

The front part 6 also includes the front wall 13 of the body and the top wall 14 thereof, the latter being provided with a lock 15 adapted to coact with a keeper 16 at the top of the rear part 7 whereby the two parts of the cabinet body may be locked in operative position.

The lower portion of the rear part 7 is formed with a forwardly inclined extension 17 and the front wall 13 is provided with a similarly arranged extension 18 and, when the parts of the cabinet are closed, a dispensing slot 19 is thus provided between the extensions 17 and 18 to facilitate the withdrawal of towels for use.

A guard plate 20 is pivotally secured to the

under side of the rear extension 17 by hinges 21 and is normally held in raised position by the tension of a spring wire 22 arranged between the extension 17 and the guard plate 20. Both ends of the spring wire are bent angularly, one being secured by a strap 23 to the extension 17 and the other being secured by a strap 24 to the inside of the guard plate 20. The medial portion of the spring wire is held against undue displacement by a strap 25.

The guard plate 20 extends throughout the length of the slot 19 and is curved so as to closely fit beneath the oppositely inclined extensions 17 and 18 to enclose and protect the projecting end 26 of the lowermost paper towel. Flanges 27 are formed at the ends of the guard plate to strengthen it and a handle 28 is struck therefrom for convenience of manipulation.

Angular stop members 29 are secured to the under side of the inclined extension 17 and coact 20 with the opposite extension 18 when the front part 6 is moved forwardly and downwardly to open position, whereby the front part is held in the horizontal position illustrated in Fig. 6 for the convenience of the operator in refilling the 25 cabinet with a fresh supply of paper towels. During the opening of the front body part 6, the front edge of the guard plate 20 slides along the inclined extension 18 to the position shown in Fig. 4 and is so held until the front part 6 is 30 restored to closed position. When the guard plate is in closed position the stops 29 are accommodated in openings 30 of said plate.

In use, the spring 22 normally holds the guard plate 20 in closed position as shown in Figs. 1 35 and 2 in which it covers the exposed projecting edge of the lowermost paper towel and also the slot 19. The tension of the spring 16 is such as to require the steady application of pressure by one hand of the user to retain it in open 40 position while the other hand is used to withdraw the towel. This mode of operation discourages the extravagant and wasteful use of the towels as by withdrawing first one with one hand and then another with the other hand. 45 Upon release of the cover plate, it is swung to closed position by the spring 22 and retained until further use.

What I claim is:

1. A towel cabinet comprising a body composed 50 of two parts pivotally connected together and having a dispensing slot therein, a spring closed guard member normally covering said slot and pivotally secured to one of said body members, said guard being engageable by the other body 55

member during swinging movement of the latter to cause displacement of said guard.

2. A towel cabinet comprising a body composed of two parts pivotally connected together and having a dispensing slot therein, a spring closed guard member normally covering said slot and pivotally secured to one of said body members, said guard being engageable by the other body member during swinging movement of the latter to cause displacement of said guard, and means for limiting the swinging movement of the second mentioned body member.
3. A towel cabinet comprising a body composed of two parts pivotally connected at their lower

ends and including lower inclined extensions normally disposed in spaced relation to provide a slot for the withdrawal of paper towels, stop members on one part of said body adapted to cooperate with the extension of the other part to limit the swinging movement of the latter, a guard pivotally secured to said body and normally covering said slot, and spring means secured to said body and normally retaining the guard in closed position, said guard being engageable by the second mentioned body part and movable to open position during the opening movement of said second mentioned body part. 10
